COMBINED ESCUTCHEON AND FACE PLATE FOR A TELEVISION RECEIVER CABINET

James K. Gerrie, Wilmette, and Jean O. Reinecke, Oak Park, Ill., assignors to Zenith Radio Corporation, a corporation of Delaware

Application October 3, 1956, Serial No. 43,215

Term of patent 7 years

(Cl. D56—4)

The figure is a perspective view of a combined escutcheon and face plate for a television receiver cabinet showing the new design.

The side of the combined escutcheon and face plate for a television receiver cabinet not shown in the drawing is identical to the side shown. The bottom of the combined escutcheon and face plate for a television receiver cabinet is unornamented.

The dominant features of the design reside in those portions shown by means of full lines in the drawings.

We claim:

The ornamental design for a combined escutcheon and face plate for a television receiver cabinet, substantially as shown and described.
